AUTOMOTIVE VEHICLE DIAGNOSTIC LANE

Charles W. MacMillan, Rock Island, Ill., assignor to Bear
Manufacturing Company, Rock Island, Ill., a corpora-
tion of Delaware

Filed Sept. 27, 1965, Ser. No. 87,180

Term of patent 14 years

(Cl. D52—6)

The drawing figure is a perspective view of an automotive vehicle diagnostic lane showing my new design.

The rear side of the partition wall and the rear sides of the instruments at the left side of the lane are substantially plain.

The portions of the drawing shown in broken lines are depicted for illustrative purposes only, and the left platform corner of the lane is shown fragmentarily for convenience of illustration.

I claim:

The ornamental design for an automotive vehicle diagnostic lane, substantially as shown and described.
